(57) **CLAIM**

I claim the ornamental design for a combination bottle and toothbrush holder, as shown and described.

DESCRIPTION

FIG. 1 is a perspective view for a combined bottle and toothbrush holder showing my new design thereof;
FIG. 2 is a front elevational view thereof;
FIG. 3 is a right side elevational view thereof;
FIG. 4 is a rear elevational view thereof;
FIG. 5 is a left side elevational thereof;
FIG. 6 is a top plan view thereof; and,
FIG. 7 is a bottom view thereof.
